UNITED STATES PATENT OFFICE.

HENRY O. FLETCHER, OF BRIDGEPORT, CONNECTICUT, ASSIGNOR TO THE SINGER
MANUFACTURING COMPANY, A CORPORATION OF NEW JERSEY.

BOBBIN-CASE LOCK.

Application filed April 10, 1919. Serial No. 288,974.

To all whom it may concern:

Be it known that I, HENRY O. FLETCHER, a citizen of the United States, residing at Bridgeport, in the county of Fairfield and 5 State of Connecticut, have invented certain new and useful Improvements in Bobbin-Case Locks, of which the following is a specification, reference being had therein to the accompanying drawings.

10 This invention relates to a mechanism for retaining the bobbin case within the shuttle of a sewing machine, being more particularly designed for use in shoe sewing machines of the outsole or rapid stitcher type, although 15 it is not limited to such use.

It provides a simple mechanism for the purpose which offers no substantial obstruction to the passage of the needle thread about the bobbin and which may be moved 20 readily to inoperative position so that the bobbin may be freely removed from the bobbin case.

More particularly this invention provides a retaining arm pivoted to extensions of the 25 shuttle retaining plate, and constructed to be swung in front of the bobbin and latched in that position, being further provided with an operating handle or finger arranged to 30 unlatch the arm and swing it away from the bobbin case by a single continuous motion.

Other objects and advantageous details of construction will be apparent from a more 35 complete description of one embodiment of the invention shown in the accompanying drawings in which,—

Fig. 1 is an elevation of a portion of a sewing machine sufficient to show the invention; and

40 Fig. 2 is a top plan view of the same portion.

A represents a portion of the machine frame constructed to house a shuttle in proper position relative to the usual sewing instrumentalities. As shown the shuttle 1 is of rotating type being driven by lugs 2 and 3 of any suitable driving mechanism. A retaining plate 4 is attached to the forward end of a portion A of the frame to 45 retain the shuttle within its raceway, one-half of which is formed in the portion A, and one-half formed in the retaining plate 4. Retaining plate 4 is provided with outstanding brackets 5 and 6 having aligned 50 openings at the outer ends thereof to receive

a pintle pin 7. Journaled on the pintle pin is the bobbin-retaining arm 8, which is adapted to extend across the front face of the shuttle, abutment 9 thereon contacting with the retaining plate 4 at the opposite side from the pintle 7. Arm 8 has a downwardly extending portion 10 having a guideway 11 therein adapted to engage on opposite sides of a lug 12 carried by the bobbin case 13 which is shown as contained within the shuttle 1 and eccentric thereto. When the arm is in the position shown, extension 10 with the guideway 11, retains the bobbin case within the shuttle and prevents it from rotating about its own axis, but allows the 60 loop of needle thread to pass therebetween. At its free end arm 8 is provided with a spring-pressed latch 14 having a hook 15 constructed to engage a lug 16 fixed on the portion A of the frame, and to be urged into 65 retaining position by means of a spring 17 seated within a suitable housing 18 in arm 8 and bearing at its outer end against the extension 19 of the latch. A latch-releasing lever or finger 20, preferably integral with 70 latch 14, extends outwardly from frame A 75 as shown.

In the operation of this device, the bobbin and bobbin case having been inserted in the forward face of the shuttle 1, the arm 8 being unlatched and retracted for the purpose, this arm is then swung up against the retaining plate 4, the abutment 9 contacting therewith, whereupon the latch member 14 springs of its own accord into latching position, riding up the forward face of lug 16, while the lug 12 on the bobbin case which also serves as a thread guide for the bobbin thread is engaged within the guideway 11. When it is desired to release the bobbin case 80 the operator pulls lever or finger 20 outwardly. This serves to first retract the latch 14 from engagement with the lug 16 and a further continuous motion exerted on finger 20 swings the retaining arm 8 about 85 the pintle 7 from in front of the bobbin case, which is then free to be removed from the shuttle. While this device as shown is applied to a shuttle of the rotating type, the bobbin being placed eccentrically thereof, it 90 is evident that with slight modifications it could also be applied to a revolving shuttle having a concentric bobbin case or to a 95 shuttle of the oscillating type, all these types of shuttles being old and well known. 100

110

Having thus described one embodiment of my invention, though it is evident that the invention is not limited thereto, but that many changes might be made therein without departing from its spirit or scope, what is claimed is,—

1. In a sewing machine having sewing instrumentalities including a shuttle and a bobbin case therein, mechanism for retaining said case in position within said shuttle, comprising a retaining arm constructed to engage said case, a hook disposed at the free end of said arm to hold the latter in engaging position, and means carried by said arm and actuatable to first release said hook and then remove said arm from engaging position.
2. In a sewing machine having sewing instrumentalities including a shuttle and a bobbin case therein, mechanism for retaining said case in position within said shuttle, comprising a pivoted arm, a latch member on the free end of said arm and arranged to engage a fixed member to hold said arm in retaining position, and means actuatable to first retract said latch member and then to remove said arm from retaining position.
3. In a sewing machine having sewing instrumentalities including a shuttle and a bobbin case therein, mechanism for retaining said case in position within said shuttle, comprising a retaining arm pivoted at a fixed point adjacent said shuttle and extending across the face thereof when in retaining position, a resilient latch carried at the free end of said arm and constructed to engage a fixed lug to hold said arm in retaining position and means for releasing said latch.
4. In a sewing machine having sewing instrumentalities including a shuttle and a bobbin case therein, mechanism for retaining said case in position within said shuttle, comprising a retaining arm pivoted at a fixed point adjacent said shuttle and extending across the face thereof when in retaining position, a resilient latch carried at the free end of said arm and constructed to engage a fixed lug to hold said arm in retaining position, and means carried by said arm for releasing said latch.
5. In a sewing machine having sewing instrumentalities including a shuttle and a bobbin case therein, mechanism for retaining said case in position within said shuttle, comprising a retaining arm pivoted to swing so as to extend across the face of said shuttle when in retaining position, and a latch pivoted to said arm on a pivot substantially parallel to the pivot of said arm, and provided with a releasing finger whereby a continuous movement of said releasing finger will first release said latch and then swing said arm out of retaining position.
6. In a sewing machine having sewing instrumentalities including a shuttle and a bobbin case therein, mechanism for retaining said case in position within said shuttle, comprising a retaining arm pivoted to swing so as to extend across the face of said shuttle when in retaining position, and a latch pivoted to said arm on a pivot substantially parallel to the pivot of said arm, and provided with a releasing finger whereby a continuous movement of said releasing finger will first release said latch and then swing said arm out of retaining position.
7. In a sewing machine having sewing instrumentalities including a shuttle, the combination of a shuttle raceway, a shuttle mounted to move therein, a plate to retain said shuttle in said raceway, a bobbin case in said shuttle, and means carried by said retaining plate at one side of said shuttle and adapted to contact with said retaining plate at the other side of said shuttle for holding the bobbin case within the shuttle.
8. In a sewing machine having sewing instrumentalities including a shuttle, the combination of a shuttle raceway, a shuttle mounted to move therein, a plate to retain said shuttle in said raceway, a bobbin case in said shuttle, an arm pivoted at one side of said shuttle on said plate and constructed to be swung across the face of said bobbin case and to contact with said plate on the other side of said shuttle, a pivoted latch at the free end of said arm, and a latch-releasing finger therefor by a continuous motion of which the latch may be released and the arm swung away from across the face of said bobbin case.

In testimony whereof, I have signed my name to this specification.

HENRY O. FLETCHER.
